(57) **CLAIM**

What is claimed is the ornamental design for a hooded backpack, as shown and described.

DESCRIPTION

FIG. 1 shows a left side view of a hooded backpack in a position of use with hood attached.

FIG. 2 shows a rear view thereof with straps in an open position.

FIG. 3 shows a front perspective view thereof with straps in a relaxed position and the hood detached.

FIG. 4 shows a front view thereof.

FIG. 5 shows a right side view thereof.

FIG. 6 shows a rear view thereof; and,

FIG. 7 shows a right side view of the hood portion thereof in a detached position.

The broken lines crossing the shaded areas represent stitching, whereas all other broken lines are directed to environment and are for illustrative purposes only. The broken lines form no part of the claimed design.
